TYPE-WRITING MACHINE

No. 829,494.

Specification of Letters Patent.
Application filed November 9, 1905. Serial No. 286,539

Patented Aug. 28, 1906.

To all whom it may concern:

Be it known that I, FRANZ X. WAGNER, a citizen of the United States, residing in Bronx borough, New York city, in the county of New York and State of New York, have invented certain new and useful Improvements in Type-Writing Machines, of which the following is a specification.

This invention relates to the type-bars and type-bar pivots of those machines in which all the type-bars are mounted, usually in a segment, upon one side of the printing-point. In such machines it is necessary to make the type-bars so short that their weight will not be an objection in operation, and it has been found very difficult in practice to assemble upon one side of the printing-point and out of the way of the platen and its appurtenances as large a number of type-bars as is desirable. Accordingly type-writing machines are almost universally manufactured with about forty type-bars to include the alphabet, figures, and punctuation-marks, although in many machines less than forty are employed. It is usual to provide each type-bar with two types for upper and lower case letters and also for additional punctuation and accent marks.

In order to equip a machine for writing the Russian language, it is necessary to provide several more characters than can be placed upon either forty or forty-two type-bars. In machines as usually manufactured the long or double types at the extremes of the system lie almost end to end, so that it becomes impracticable within the limited space to add several more type-bars at the ends of the system if the same plan or disposition of the type-bars is to be followed for the additional or auxiliary as for those in the main system. It is highly desirable, however, from an economical standpoint to employ for writing the Russian and other languages machines such as are regularly manufactured and with as little change therein as possible, and to this end I have contrived to add auxiliary bars to the ends of the usual system of forty-two bars in such a manner that but very little additional space is occupied by the auxiliary bars and types, so that it is rendered practicable to add to regularly-manufactured machines enough types to adapt them to the Russian and other languages.

Usually all the type-bars in the system are

hung upon a single fulcrum-rod, which forms 55 a segment of a circle, or are arranged with their pivots disposed in a circle, the type-bars being of substantially uniform length and their pivots about equidistant from the printing-point. To each end of such a system I add, preferably, three auxiliary bars, the first of which is shorter than the main bars and is fulcrumed nearer the printing-point than the main bars. The second is shorter than the first and fulcrumed still 60 nearer the printing-point, and the third is shorter than the second and fulcrumed still nearer to the printing-point. Owing to this modification in the lengths and pivots of the auxiliary bars, their types are brought into 65 very compact relation with one another and with the extreme type in the main system, so that the length of the type-bar segment is not unduly increased. The six auxiliary type-bars enable the employment of twelve 70 additional characters.

In the accompanying drawings, Figure 1 is a rear elevation of the type-bar segment of the well-known "Underwood" front-strike writing-machine, showing my improvements 80 applied thereto in one form. Fig. 2 is a sectional elevation showing a type-bar in printing position. Fig. 3 shows the type-bars that are mounted upon the right-hand half of the segment, including the auxiliary bars. In 85 this figure the bars are shown in the positions they would occupy if their fulcrum-rod were straightened and made horizontal—that is, if their pivots were changed from the arrangement seen at Fig. 1 and placed in one 90 straight horizontal line. In this figure the types show substantially the same relation each to the next as they bear in the usual curved or segmental type-basket.

1 designates the platen of said type-writing machine, upon the front side of which strike multiple types 2, carried upon radiating type-bars 3, which are mounted upon a fulcrum-rod 4, which is usually in the form of a segment of a circle. The type-bars work 95 in radiating-slots 5, formed upon the lower border of a vertical segment 6. The main system is illustrated as comprising forty-two type-bars, although some styles of Underwood and other machines carry a smaller 100 number. The first auxiliary type-bar at each end of the system is designated as 7, the next as 8, and the third as 9, and they are all 105

pivoted in the same vertical plane as the type-bars in the main system. The type-bar 7, however, is shorter than the main type-bars and is mounted upon a pivot 10, which is correspondingly shorter than the main type-bars. The type-bar 8 is shorter than the type-bar 7 and is mounted upon a pivot 11, which is nearer than 10 to the printing-point. The type-bar 9 is shorter than 8 and mounted upon a pivot 12, which is nearer than 11 to the printing-point. These pivots 10, 11, and 12 may be formed integral, as illustrated, and secured by solder or otherwise to the segment 6, and, if desired, this zigzag pivot member 15 may at one end be provided with a pivot 13 for the extreme main type-bar 3, such portion 13 adjoining the main fulcrum-wire 4, as seen at Fig. 1. The pivots of the auxiliary bars may, however, be otherwise formed and 20 supported in connection with either the main system shown or other main systems.

It will be seen from Figs. 1 and 3 that the auxiliary type-bars are close together as compared with some of the extreme type-bars in the main system, but that their types have 25 employed clearances from one another and from the extreme type 2 in the main system. Beginning with the middle of the system, the multiple types are set at increasing angles 30 with their bars until the final auxiliary type (designated as 14) is nearly at right angles with its bar; but it will be seen that the auxiliary types instead of lying substantially end to end are placed substantially one behind 35 another, according to the progressively-diminishing lengths of their bars.

It will be understood that the type-bars at the left hand of the system correspond in position and otherwise with those illustrated 40 at Fig. 3.

Having thus described my invention, I claim—

1. In a type-writing machine, a series of radiating type-bars all upon one side of a common printing-center, and of approximately equal length and pivoted in an arc of a circle; each type-bar carrying a multiple type, the types at the middle of the series being about in line with their bars and the types 45 from the middle to the end of the series lying at progressively-increasing angles to their bars; and auxiliary type-bars mounted at the ends of said series, and shorter than the bars in said series and pivoted nearer the printing-center.

2. In a type-writing machine, a series of radiating type-bars all upon one side of a common printing-center, and of approxi-

mately equal length and pivoted in an arc of a circle; each type-bar carrying a multiple 60 type, the types at the middle of the series being in line with their bars, and the types from the middle to the end of the series lying at progressively-increasing angles to their bars; and three auxiliary type-bars mounted at 65 each of the ends of said series, the first auxiliary bar being shorter than the bars in said series and pivoted nearer the printing-center, the second auxiliary type-bar being shorter than the first auxiliary type-bar, and pivoted 70 still nearer to the printing-center, and the third auxiliary type-bar being shorter than the second and pivoted still nearer the printing-center.

3. In a type-writing machine, the combination with a segment having slots, of type-bars working in said slots, a curved fulcrum-wire mounted upon said segment for said type-bars, and pivots offset from said curved wire and nearer to the printing-center, for the 80 type-bars at the extremities of said segment.

4. In a type-writing machine, the combination with a segment having slots, of type-bars working in said slots, a curved fulcrum-wire mounted upon said segment for said 85 type-bars, and pivots offset from said curved wire and nearer to the printing-center, for the type-bars at the extremities of said segment; the type-bars mounted upon said offset pivots being shorter than the remaining 90 type-bars.

5. In a type-writing machine, the combination with a segmental support, of relatively long type-bars pivoted in a unitary curve extending substantially from end to 95 end of the segmental support, a stepwise series of type-bar pivots at each extremity of said segmental support, and relatively short type-bars mounted upon said stepwise pivots and progressively shorter than one 100 another.

6. In a type-writing machine, the combination with a segment having slots, of type-bars working in said slots, a curved fulcrum-wire mounted upon said segment for said 105 type-bars, pivots offset from said curved wire and nearer to the printing-center, for the type-bars at the extremities of said segment; the type-bars at said extremities being shorter than the remaining type-bars, and 110 the slots for said shorter type-bars being deeper than the remaining slots.
